(57) **CLAIM**

The ornamental design for an electrical lead connector as shown and described.

DESCRIPTION

FIG. 1 is a top, rear, left side perspective view of an electrical lead connector showing our new design.

FIG. 2 is a top, front, right side perspective view thereof.

FIG. 3 is a bottom, front, right side perspective view thereof.

FIG. 4 is a rear elevation view thereof.

FIG. 5 is a right side elevation view thereof.

FIG. 6 is a top plan view thereof.

FIG. 7 is a left side elevation view thereof.

FIG. 8 is a front elevation view thereof; and,

FIG. 9 is a bottom plan view thereof.

The broken lines show portions of the electrical lead connector that form no part of the claimed design.
